CLAIM

The ornamental design for a holder for pamphlets or the like, as shown and described.

DESCRIPTION

FIG. 1 is a front, top and left side perspective view of a holder for pamphlets or the like showing my new design;

FIG. 2 is an enlarged side elevational view taken from the right of FIG. 1;

FIG. 3 is an enlarged front elevational view thereof;

FIG. 4 is an enlarged rear elevational view thereof;

FIG. 5 is an enlarged top plan view thereof;

FIG. 6 is an enlarged bottom plan view thereof;
